UNITED STATES PATENT OFFICE.

HUGO STRACHE AND PHILIPP PORGES, OF VIENNA, AUSTRIA-HUNGARY.

PROCESS FOR CONVERTING HEAVY HYDROCARBONS INTO LIGHT HYDROCARBONS.

1,205,578.

Specification of Letters Patent. Patented Nov. 21, 1916.

Application filed May 13, 1914. Serial No. 838,279.

To all whom it may concern:

Be it known that we, Dr. HUGO STRACHE and PHILIPP PORGES, both subjects of the Emperor of Austria-Hungary, and residing 5 at Vienna, Austria-Hungary, have invented certain new and useful Improvements in Processes for Converting Heavy Hydrocarbons into Light Hydrocarbons; and we do hereby declare the following to be a full, 10 clear, and exact description of the invention, such as will enable others skilled in the art to which it appertains to make and use the same, reference being had to the accompanying drawings, and to letters or figures of 15 reference marked thereon, which form a part of this specification.

In known methods of transforming heavy hydrocarbons into light, easily vaporizable hydrocarbons, in which a mixture of the 20 heavy hydrocarbon, petroleum, vapor and steam are conducted over a heated metal oxid to produce light hydrocarbons and combustible gas, there has been a great disadvantage in that the metal oxid for transferring oxygen became inoperative in a comparatively short time by a part of the metal oxid being reduced to metal, and by carbon depositing on the catalyzer. Another great 25 disadvantage in this process is that there has been no reliable indication when the oxygen transfer required regeneration, and, furthermore, the regeneration has customarily been done by conducting superheated steam over the hot, depleted oxygen trans- 30 ferrer, often causing explosions.

According to the present invention all or practically all of the heavy hydrocarbons are converted into light hydrocarbons and gas, with some carbon deposits on the 40 oxygen transerrer, and to this end vapors of heavy hydrocarbon, gas-oil, mixed with steam are conducted over an oxygen transerrer at a comparatively low temperature, thus giving a large output in light hydro- 45 carbon or benzin or gasolene, having a low boiling point, and but small quantities of gas, the object being, in all of these processes to reduce the gas production to a minimum.

The oxygen transerrer is an oxid of a 50 metal, for example, iron-oxid, lead-oxid, cerium-oxid, pyrolusite, or the like, and is preferably the oxid of a metal having more than one stage of oxidation.

The regeneration of the substance, which 55 becomes more or less mixed or coated with carbon during the process, is effected by con-

ducting oxygen or air through the heated catalyzer. This coating of carbon is practically negligible when the proper supply of steam is maintained and the temperature 60 kept low. The cracking smell is also greatly reduced when care is taken to promptly re-oxidize the oxygen transerrer as soon as the yield of light oils begins to decrease.

In order that the operation of the invention may be understood, reference will be had to the accompanying drawing, in which—

B is a distilling vessel containing the heavy hydrocarbon or mineral oil to be 70 treated, for example, gas-oil, known commercially as "green oil" or "blue oil" such oils having a density of 0.8 to 1.0, and beginning to boil at 150° C.

Steam is conducted into the vessel B, and 75 the mixed steam and heavy hydrocarbon vapor pass through valve b to the retorts A filled with a substance capable of transferring oxygen to the oil. Said retorts A are contained in a furnace C, and are heated 80 by gas jets from a pipe h the distillation in the presence of steam taking place at a temperature between 140° C. at the beginning of the operation and is gradually raised to 300° C. The decomposition in the re- 85 torts A takes place when the temperature of the retorts reaches about 600° C. The quantity of the oxygen transerrer used is dependent upon the quantity of oil to be treated in a unit of time; for example, if 90 100 kg. of oil is to be converted into gaso- lene in one hour, 100 kg. of catalyzer (iron oxid) will be required.

The products of reaction pass from the 95 retorts A filled with metal oxid O to a dephlegmator D from which the heavier constituents are returned by a pipe r to the vaporizer B, while the lighter constituents or gaseous products pass to a purifier R provided with a mass S containing lead oxid 100 and an alkali or an alkaline earth, by which the cracking smell, olefins, are removed. The light hydrocarbon is then condensed in a cooler K₁ at a temperature of about +15° C., and the lighter gases are then conducted 105 to a second cooler K₂ and cooled to a temperature of about -10° C.; the uncondensed gases issue from the pipe g₁. These gases either escape, or are used for heating the vaporizer and retorts, or may be compressed 110 into containers for future use.

After about six hours of operation, the

gasolene or benzin flow from the cooler K_1 will begin to show an increasing percentage of hydrocarbons having a boiling point of over $150^\circ C$. This is an indication that the transformation of the heavy to the lighter hydrocarbons is not progressing satisfactorily, and that the oxygen transferrer requires regeneration. Valves b and d are now closed and valves a and a_1 are opened, 10 the valve a admitting air or oxygen, which is energetically blown by a blower c through the heated retorts A effecting the combustion of the deposited carbon and the re-oxidation and the oxidation to a higher 15 stage of the oxygen transferrer. The products of combustion leave the retorts and pass out through the valve a_1 , where the nature of the gas or flame of the ignited gas, or the absence of flame, will determine 20 when the regeneration has been completed. Valves a and a_1 are then closed and valves b and d again opened, and the process continued as before. By regenerating the oxygen transferrer in this manner its original 25 effectiveness is not only restored, but after repeated regeneration the transferrer becomes more effective than when first used, probably due to the opening up of its surfaces, so that the process can be carried out 30 at a lower temperature, (with an iron oxid as oxygen transferrer, between $500^\circ C.$, and $600^\circ C.$) and the quantity of uncondensable gas is considerably reduced, while the valuable product desired to be obtained, namely 35 gasolene, or benzin, is increased in volume.

We claim—

1. The process of converting heavy hydrocarbon oils into light hydrocarbon oils, which comprises passing a mixture of a 40 heavy oil vapor and steam over a metal oxid capable of transferring oxygen to the

decomposition products of said oil and heated to a temperature sufficient to cause the formation of light hydrocarbon oils capable of immediate industrial use without the 45 formation of tar and carbon.

2. The process of converting heavy hydrocarbon oils into light hydrocarbon oils, which comprises passing a mixture of heavy oil vapor and steam at substantially atmospheric pressure and without destructive distillation, over the oxid of a metal capable of more than one stage of oxidation and of being reduced to metal at the temperatures employed, and heated to substantially a red 55 heat, the quantity of steam being proportioned to prevent the formation of tar and carbon.

3. The process of converting heavy hydrocarbon oils into light hydrocarbon oils, which comprises passing a mixture of heavy oil vapor and steam at substantially atmospheric pressure and without destructive distillation over the oxid of a metal capable of more than one stage of oxidation and of being reduced to metal at the temperatures employed, and heated to substantially a red heat, the quantity of steam being proportioned to prevent the formation of tar and carbon, and periodically passing a 60 rapid current of air in contact with said oxid when the yield of light hydrocarbons begins to decrease.

In testimony that we claim the foregoing as our invention, we have signed our names 75 in presence of two subscribing witnesses.

DR. HUGO STRACHE.
PHILIPP PORGES.
